Attorney

UNITED STATES PATENT OFFICE.

DAVID M. WALL, OF PROVIDENCE, RHODE ISLAND.

BLADE PENDANT.

Application filed August 18, 1922. Serial No. 582,711.

To all whom it may concern:

Be it known that I, DAVID M. WALL, a citizen of the United States, residing at Providence, in the county of Providence and State of Rhode Island, have invented certain new and useful Improvements in Blade Pendants, of which the following is a specification.

My invention relates to blade pendants and has for its essential objects adaptability for suspension from a chain; the combination of a pendant with a cutting implement; utility for the use of blade of different types, shapes, and sizes; capacity for substitution of blades; security; clamping efficiency; facility of operation; and inexpensiveness of construction.

To the above ends essentially my invention consists in such parts and in such combinations of parts as fall within the scope of the appended claims.

In the accompanying drawings which form a part of the specification—

Figure 1 is a side elevation of a pendant embodying my invention,

Figure 2, a section on line 2—2 of Figure 1,

Figure 3, a section on line 3—3 of Figure 2,

Figure 4, a like section of the same in open position, and

Figure 5, a perspective view of the clamping member.

Like reference characters indicate like parts throughout the views.

In detail my device comprises an oblong flat tubular sheet metal casing 7 open at both ends having parallel front and rear walls 8 and preferably transversely curved side walls 9 provided near their upper extremities with stops or projections 11 formed by indentation. Detachable caps 13 and 14 fit over the top and bottom ends respectively of the casing and form closures.

These caps while slidably engaged with the casing have a sufficient frictional contact therewith to prevent accidental disengagement. In an integral knob 15 on the cap 13 is a suspension ring 16 to afford attachment to a chain.

Slidably mounted in the casing is a clamp member 17 cooperating with the front and back sides of the casing to retain a blade,

in this instance a perforated two edged razor blade 18, although obviously an unperforated single edge blade may be carried with equal facility. In detail the clamping member is constructed by cutting and bending up by suitable tools from a piece of resilient sheet metal an oblong blank which is centrally bent to form an end substantially closed loop 20 integral with the upper ends of two slightly diverging resilient arms 21, convexo-concave in cross section, having integral with their lower portions laterally extending wings or plates 22 of a width to slide with their lateral edges in contact with the casing sides 9 until stopped by contact with the projections 11. The plates 22 have preferably centrally disposed vertical outwardly swelled portions 24 continuous with the arms 21 and partaking of the outward inclination of the latter. These swells or shoulders engage the front and rear walls of the casing, and as they slide into the casing are compressed so as to force the plates 22 into contact or adjacent each other.

The operation of my device is as follows. A blade is manually inserted between the arms 21 of the clamping member while the latter is entirely removed from the casing. By the finger and thumb the operator compresses the plates 22 to temporarily hold the blade, and the member 7 is then slid into the casing with the loop 20 uppermost, and the cap 14 applied as shown in Figure 3. When it is desired to use the knife the casing is withdrawn from the cap 13 and the loop 20 is grasped by the thumb and finger and drawn upwardly until the plates contact with the projections 11 and the parts assume the position shown in Figure 4 ready for cutting purposes. The blade is held tightly clamped between the edges of the arms 21 by virtue of their compression by the front and back walls of the casing.

I claim,—

1. In a blade pendant, a casing provided with open ends, detachable caps on the ends of the casing, and a compressible clamp member slidably mounted in the casing operable by contact with the casing to frictionally clamp the blade.

2. In a blade pendant, a casing provided with open ends, detachable caps on the ends of the casing, a compressible clamp member

of greater length than the casing slidably mounted in the casing to frictionally clamp the blade and compressed by the casing.

3. In a blade pendant, a flat casing provided with open ends, and a clamping member comprising diverging resilient clamping arms enclosable in the casing, a loop connecting the upper ends of the arms above

the casing, and plates rigid with the lower ends of the arms engageable with the walls of the casing to compress the arms to frictionally clamp the blade. ¹⁰

In testimony whereof I have affixed my signature.

DAVID M. WALL.
